(57) **CLAIM**

The ornamental design for a supercooled beverage crystallization slush device with illumination, as shown and described.

DESCRIPTION

FIG. 1 is an upper front left perspective view of a supercooled beverage crystallization slush device with illumination showing my new design;

FIG. 2 is an upper front right perspective view of the slush device of FIG. 1.

FIG. 3 is an upper rear right perspective view of the slush device of FIG. 1.

FIG. 4 is an upper rear left perspective view of the slush device of FIG. 1.

FIG. 5 is a front view of the slush device of FIG. 1.

FIG. 6 is a rear view of the slush device of FIG. 1.

FIG. 7 is a left side view of the slush device of FIG. 1.

FIG. 8 is a right side view of the slush device of FIG. 1.

FIG. 9 is an enlarged top plan view thereof; and,

FIG. 10 is an enlarged bottom plan view thereof.
